UNITED STATES PATENT OFFICE

161,337

RESPIRATOR OR SIMILAR ARTICLE

John D. Hill, Cleveland, Ohio

Application July 1, 1949, Serial No. 3,659

Term of patent 14 years

(Cl. D83—1)

To all whom it may concern:

Be it known that I, John D. Hill, a citizen of the United States of America, residing at Cleveland, in the county of Cuyahoga and State of Ohio, have invented a new, original, and ornamental Design for a Respirator or Similar Article, of which the following is a specification, reference being had to the accompanying drawings, forming a part thereof, in which:

Figure 1 is a front perspective view of a respirator or similar article from the outside thereof, showing my new design;

Fig. 2 is a front view of the respirator;

Fig. 3 is a side view of the respirator;

Fig. 4 is a top plan view of the respirator; and

Fig. 5 is a perspective rear quarter view of the respirator showing the inside thereof.

The head strap is shown broken away in Figs. 2, 3, 4, and 5 for convenience of illustration.

The characteristic features of my design reside in the portions of the respirator illustrated in solid lines.

I claim:

The ornamental design for a respirator or similar article, substantially as shown and described.

JOHN D. HILL.
